UNITED STATES PATENT OFFICE.

AMOS WILLIAMS, OF EAST TOLEDO, OHIO.

SPARK PLUG.

Application filed June 21, 1922. Serial No. 569,894.

To all whom it may concern:

Be it known that I, Amos Williams, citizen of the United States, residing at East Toledo, in the county of Lucas and State of 5 Ohio, have invented certain new and useful Improvements in Spark Plugs, of which the following is a specification.

This invention relates to an improved spark plug and seeks, as one of its principal 10 objects, to provide a plug wherein the gap surfaces of the electrodes may be readily cleaned without removing the plug from an engine cylinder.

The invention has as a further object to 15 provide a plug embodying a visible gap whereby the functioning of the plug may be readily ascertained at any time.

And the invention has as a still further 20 object to provide a plug which will be characterized by extreme structural simplicity and which will be well adapted for use in connection with any conventional make of internal combustion engine.

Other and incidental objects will appear 25 hereinafter.

In the drawing:

Figure 1 is a side elevation of my improved spark plug.

Figure 2 is a vertical sectional view taken 20 medially through the device.

Figure 3 is a transverse sectional view on the line 3—3 of Figure 1, looking in the direction of the arrows, and

Figure 4 is a fragmentary elevation showing 35 a slightly different embodiment of the invention.

In carrying the invention into effect, I employ a shell 10 threaded at its lower end for engagement in the usual spark plug opening of an engine cylinder and depending from the lower end edge of the shell are oppositely disposed ground electrodes 11 extending toward each other beneath the shell. Removably fitting in the shell is an insulator 12 which may be of porcelain or other 40 approved material and surrounding the insulator is a nut 13 threaded into the shell for clamping the insulator in position. Mounted upon the insulator at its upper end is a metal band 14 crimped at its lower margin into a surface groove in the insulator and slidably fitting through the insulator axially thereof is a central electrode 15. At 45 its lower end this electrode is provided with a disc 16 and at a point spaced above the disc with a collar 17 confronting the lower

end of the insulator and interposed between said collar and the insulator is an appropriate packing gasket 18 surrounding the electrode. Formed on or otherwise secured to the electrode near its upper end is a collar 19 and bearing between said collar and the upper end of the insulator is a spring 20 pressing the electrode upwardly for normally holding the disc 16 spaced above the ground electrodes 11 to provide spark gaps between said disc and the electrodes while also binding the gasket 18 between the collar 17 and the insulator to form a closed joint between the central electrode and the insulator. A gasket 20' of suitable insulating material is arranged between the lower end of the spring and the insulator and fixed to the electrode 15 at its upper end is a dielectric knob 21, this knob abutting the collar 19.

Formed in the insulator 12 near its upper end is, as shown in detail in Figure 3, an opening 22 intersecting the central electrode 15 and intersecting said opening at substantially right angles thereto is a somewhat larger sight opening 23. Registering with the latter opening is an opening 24 in the wall of the band and confined between the band and the insulator is a transparency 25 closing the sight opening. Threaded through the wall of the band to extend into the opening 22 is an electrode 26 cooperating with the central electrode to form a spark gap therebetween and, of course, the electrode 26 may be adjusted upon the band for varying the length of said gap. Threaded upon said electrode is a locking nut 27 abutting the band and confronting said nut is a binding nut 28 upon the electrode for securing a circuit wire thereto. Thus, when a circuit is closed through said wire, current will flow through the electrode 26 to jump the gap between said electrode and the electrode 15 when the current will flow through the electrode 15 to jump the gaps between the disc 16 of the latter electrode and the ground electrodes 11. As will be appreciated, the presence of the gap between the electrodes 15 and 26 will tend to insure the functioning of the plug at the gaps between the disc 16 and the ground electrodes and, of course, the spark occurring at the former gap will be readily visible through the sight opening 23. Accordingly, the operation of the plug may be readily observed at any time. Should the plug become fouled, the

knob 21 is grasped and the central electrode 15 depressed to shift the disc 16 of said electrode into engagement with the electrodes 11 when the central electrode is then 5 rotated to grind the disc against the ground electrodes. The sparking surfaces of the central electrode and the ground electrodes may thus be readily cleaned without the necessity for removing the plug from its cylinder when, upon release of the central electrode, the spring 20 will return said electrode to its normal position so that the plug 10 may properly function. I accordingly provide a plug wherein the troubles incident 15 to fouling may be overcome with a minimum of difficulty.

In some instances, I may desire to provide the plug with an external gap for short circuiting the plug when fouled so that the 20 spark at said gap may visibly indicate the inefficient condition of the plug. In such instance, I form the band 14 at one side thereof with a depending finger 29 extending downwardly along the insulator toward 25 the nut 13 and providing an electrode terminating adjacent the nut forming a spark gap therebetween. Thus, when the disc 16 of the central electrode and the ground electrodes 11 become fouled so as to hinder the jumping 30 of the current from said disc to the ground electrodes, the current will, following the course of least resistance, flow through the finger 29 to jump the gap between said finger and the nut 13. The spark 35 occurring at said gap will thus serve to apprise the operator of the condition of the plug and since the gap is exposed, sparking at the gap will be readily visible.

In Figure 4 of the drawing, I have illustrated 40 a slightly different embodiment of the invention wherein the insulator of the plug is indicated at 29, the band at the upper end of the insulator at 30, the central electrode at 31, and the cooperating elec-

trode upon the band 30 at 32, these parts 45 corresponding to similar parts of the preferred construction. However, in the present instance, the finger upon the band 30, as illustrated in the preferred construction, is eliminated, the external gap formed by 50 said finger being omitted. Otherwise, this modification is identical with the preferred construction and further description is accordingly believed unnecessary.

Having thus described the invention, what 55 is claimed as new is:

1. A spark plug including a shell, an insulator carried thereby, a central electrode mounted upon the insulator, a band carried by the insulator, and an electrode mounted 60 upon said band to cooperate with the central electrode forming a spark gap therebetween, the band being provided with a finger extending toward the shell and forming a visible indicating spark gap between 65 such electrode and the shell.

2. In a spark plug, coacting electrodes forming an ignition spark gap, and a third electrode in shunt with one of said first mentioned electrodes and forming an indicator 70 spark gap of greater resistance than said first mentioned gap.

3. In a spark plug, coacting electrodes forming an ignition spark gap, and a third electrode at the exterior of the plug in 75 shunt with one of said first mentioned electrodes and forming a visible indicator spark gap of greater resistance than said first mentioned gap.

4. In a spark plug including a shell, coacting electrodes forming an ignition spark gap, and a third electrode in shunt with one of said first mentioned electrodes and cooperating with the shell to form an indicator 80 spark gap of greater resistance than said first mentioned gap.

In testimony whereof I affix my signature.
AMOS WILLIAMS. [L.S.]
